UNITED STATES PATENT OFFICE.

BRUCE W. DAVID, OF CLEVELAND HEIGHTS, OHIO, ASSIGNOR TO THE LINCOLN ELECTRIC COMPANY, OF CLEVELAND, OHIO, A CORPORATION OF OHIO.

METHOD OF MANUFACTURING ROTORS.

Application filed July 2, 1921. Serial No. 482,044.

To all whom it may concern:

Be it known that I, BRUCE W. DAVID, a citizen of the United States and a resident of Cleveland Heights, county of Cuyahoga, and State of Ohio, have invented a new and useful Improvement in Methods of Manufacturing Rotors, of which the following is a specification, the principle of the invention being herein explained and the best mode in which I have contemplated applying that principle, so as to distinguish it from other inventions.

In the armature windings of induction motors, such winding is placed in slots around the periphery of the laminated core of the armature. Where, as in the so-called squirrel-cage type of winding, the latter consists simply of a number of heavy copper bars placed in suitable slots, these are formed into closed circuits by means of connecting rings at the ends, which, in the case of the armature, are known as rotor end rings. The satisfactory attachment of the ends of the bars to such end rings has always been a matter of considerable difficulty, inasmuch as such attachment has to be made after the bars are in place, and the full cross-section of bars and ring must be preserved at all points if the current flow is not to be impeded.

The object of the present invention accordingly is the provision of an improved construction of such end rings, and incidentally thereto, an improved method of attaching same to the bars that constitute the winding whereby the difficulty in question may be overcome.

To the accomplishment of the foregoing and related ends, said invention, then, consists of the means and steps hereinafter fully described and particularly pointed out in the claims; the annexed drawing and the following description setting forth in detail certain means and one mode of carrying out the invention, such disclosed means and mode illustrating, however, but one of various ways in which the principle of the invention may be used.

In said annexed drawing:—

Fig. 1 is partly an axial section and partly a side elevation of an armature or rotor illustrating one form of my improved end ring construction; Fig. 2 is a sectional detail illustrating the method employed in constructing such end ring or rather in at-

taching same to the bars constituting the winding; and Fig. 3 is a similar view of a slightly modified form of construction.

In both Figs. 1 and 3 the armature or rotor 1 is shown in diagrammatic outline only, the same being mounted on the usual shaft or spindle 2. In the sectioned portion of these figures, there is shown one of the bars 3, forming part of the winding previously referred to, such bars being held in suitable transverse slots, and having their ends, as best shown in Fig. 2, slightly projecting beyond the lateral edge of the rotor.

In the specific form of construction shown in Figs. 1 and 2, these ends are homogeneously united to a ring 4 of circular cross-section formed out of a heavy wire or rod, while in Fig. 3, such ring is shown as formed out of a flat bar or annulus 4^a. In either case the external diameter of the ring is such as to permit it to fit more or less snugly just inside the projecting ends of the series of bars 3. An annular retaining plate 5 or 5^a, as the case may be, is then pressed against the corresponding end of the rotor, the outer portion of such plate being curved or bent to more or less closely conform with the corresponding ring. At the same time such plate, where the ring is of circular cross-section, will be seen to form an encircling groove or trough in which such ring lies, and over which the adjacent ends of the bars 3 project. The bars 3, as well as the ring 4, will ordinarily be of copper, although any conductor of suitable resistance may be employed, while the annular plate 5 or 5^a will preferably be of a metal having a higher melting point and need not itself be a specially good conductor of electricity. Thus ordinarily I make such plate out of steel.

With the parts preliminarily assembled in the fashion described, I then unite the ends of the bars 3 with the ring 4 or 4^a by employing a welding pencil 6 of carbon and striking an arc between the same and said ring or bars, at the same time feeding in a "melt rod" 7, preferably of the same metal as the latter. As a result the spaces between the several bars, and between such bars and the ring are filled up with molten metal from such rod, and at the same time the surfaces of the bars and ring are fused sufficiently to cause them to be homogeneously united or welded into the mass of metal thus

deposited. It will be understood that pencil 6 may itself be made of the metal which is thus to be melted in, and so be melted down directly; although the method first described is preferred in practice.

In the case of the construction shown in Fig. 1, the molten metal may be allowed to flow around the ring 4 and fill in the space between the same and the outwardly bent portion of plate 5. In the case of the construction shown in Fig. 3, where the ring 4^a is of rectangular cross-section, the space in question is more completely filled, and the metal deposited from the pencil will lie wholly on the outer face of the ring and between the ends of the rods 3. After the welding operation has been completed, the deposited metal, which may present something of an excrescence, as indicated in dotted outline in Fig. 1, may be turned off to present a smooth beveled surface, as indicated in full lines both in said figure and in Fig. 3.

The plate 5 or 5^a will be sufficiently firmly united to the end ring thus built up to securely hold such plate in place, and thus form of the same a permanent closure for the end of the rotor. While my invention has been particularly described with reference to the construction of a rotor end ring it will be obvious that an end ring may be built up in exactly the same way for use in other corresponding parts of an electrical machine, and no limitation is intended to be placed upon such use by such specific reference.

Other modes of applying the principle of my invention may be employed instead of the one explained, change being made as regards the steps herein disclosed, provided those stated by any of the following claims or their equivalents be employed.

I therefore particularly point out and distinctly claim as my invention:

1. In the manufacture of rotors for in-

duction motors and the like, the steps which consist in disposing a conductor ring adjacent the ends of the bars that constitute the winding of such rotor, holding said ring in place by means of an annular metallic plate 50 pressed against the corresponding end of said rotor, said plate having a higher fusion point than said rings and bars, and then playing an arc from a suitable electrode over such ring and rod-ends whereby the latter are interfused and united to the adjacent portion of said plate.

2. In the manufacture of rotors for induction motors and the like, the steps which consist in disposing a conductor ring adjacent the ends of the bars that constitute the winding of such rotor, holding said ring in place by means of an annular metallic plate 60 pressed against the corresponding end of said rotor, said plate having a higher fusion point than said rings and bars, playing an arc from a suitable electrode over such ring and rod-ends, and simultaneously melting a metal pencil in such arc, whereby such ring and rod-ends are interfused and united to 70 the adjacent portion of said plate.

3. In the manufacture of rotors for induction motors and the like, the steps which consist in disposing a conductor ring adjacent the ends of the bars that constitute the 75 winding of such rotor, holding said ring in place by means of an annular metallic plate having its outer edge bent to form a trough in which such ring lies, the arms of the rotor said plate having a higher fusion point 80 than said rings and bars, being maintained approximately horizontal, playing an arc from a suitable electrode downwardly onto such ring, rod-ends and the adjacent portion of the plate-edge, and simultaneously 85 melting a metal pencil in such arc, whereby such ring and rod-ends are interfused and united to such plate-edge.

Signed by me, this 24th day of June, 1921.
BRUCE W. DAVID.
